UNITED STATES PATENT OFFICE

2,671,596

CONTAINER WITH FLAT TOP AND
INTEGRAL OVERCAP

Russell C. Taylor, Greenwich, Conn., assignor to
American Can Company, New York, N. Y., a
corporation of New Jersey

Application November 18, 1948, Serial No. 60,794

6 Claims. (Cl. 229—7)

1

This invention relates to containers for the packaging and delivery of liquids, such as milk, fruit juices or the like and has particular reference to a sanitary fibre container of an improved construction embodying a one-piece combination top end member or closure and an overcap or shield for protecting the top closure from contamination.

The invention constitutes an improvement upon the container illustrated and described in United States Patent 2,085,979 issued July 6, 1937, to John M. Hothersall, and is especially an improvement on the top closure construction thereof.

The invention contemplates a liquid proof fibre container, comprising a substantially square tubular body having a top end member secured to overlapped marginal edge portions of the top end of the body and adhesively united thereto in a leak proof end seam and having an extension of the top end member folded back upon itself and functioning as a protective cover or overcap for maintaining the top surface of the container in a sanitary condition, the overcap being hingeable for exposing an opening in the top end member for filling and dispensing the contents of the container.

An object of the invention is the provision of a sanitary fibre container for milk and other products wherein the top surface of the container is covered and protected at all times against contamination from outside foreign matter.

Another object is the provision of such a container wherein an overcap or shield is provided as an integral and hingeable extension of the top end member to overlap, protect and maintain the top surface and a peripheral edge of the container in sanitary condition.

Another object is the provision of such a container wherein the hinged overcap or shield is formed with a friction plug or closure element which is engageable within a filling and dispensing opening in the top end member for closing and sealing the container and which is coactive with overlapped edges of the overcap for holding the overcap in its protective position on the container for maintaining the upper surface of the top end member clean and sanitary.

Numerous other objects and advantages of the invention will be apparent as it is better understood from the following description, which, taken in connection with the accompanying drawings, discloses a preferred embodiment thereof.

Referring to the drawings:

Figure 1 is a fragmentary perspective view of

2

the upper part of a sealed container embodying the present invention and illustrating a hinged overcap in a raised position relative to the top of the container;

5 Fig. 2 is a fragmentary enlarged sectional view of the container illustrated in Fig. 1 taken substantially along a vertical plane indicated by the lines 2—2 in that figure and showing the protective cover or overcap secured to the upper part of the container;

Fig. 3 is a fragmentary perspective view of the container illustrated in Fig. 1 with the parts shown in superimposed or exploded position preparatory to assembling;

10 Fig. 4 is a view similar to Fig. 1 showing an alternative form of the invention and illustrating a plug closure formed as an integral part of the hinged overcap and disposed in a raised position;

Fig. 5 is a fragmentary enlarged sectional view 15 of the container illustrated in Fig. 4 taken substantially along a vertical plane indicated by the lines 5—5 in that figure and showing the overcap secured to the upper part of the container with the plug closure in sealed position within the filling and dispensing opening;

Fig. 6 is a view similar to Figs. 1 and 4 showing another modification of the invention illustrating an overcap having a hingeable section extending diagonally across the top of the container; and

20 Fig. 7 is a view similar to Fig. 5 taken substantially along the vertical plane indicated by the lines 7—7 in Fig. 6 and showing the overcap secured to the upper part of the container with the plug closure in sealed position within the filling and dispensing opening.

As a preferred and exemplary embodiment of the instant invention as disclosed in Figs. 1, 2 and 3, the drawings illustrate a rectangular container comprising a fibre tubular body 11 closed at its upper end with a sanitary, flat, fibre top end member 12. The bottom end of the container may be closed in any suitable manner, such for example as disclosed in the above mentioned Hothersall patent.

25 The body 11 is formed preferably from a single sheet or blank of fibrous material folded at right angles to provide four side walls 13 and having the side edges of the sheet overlapped to form a vertical lap side seam 14. The overlapped seam edges are secured with a suitable adhesive for producing a liquid tight side seam.

The body walls 13 adjacent their upper ends are formed with inwardly extending oblique wall sections 15 (Fig. 2) which merge into short vertical wall sections 16. Extensions of the wall sec-

tions 16 are bent laterally outward into a peripheral, flat horizontal wall section 17, thence folded upwardly and horizontally inwardly in overlapping relation thereon in a wall or flange 18 which terminates at its inner edge along a vertical line substantially flush with the inner surface of the wall sections 16, defining a mouth for the container body. The flange 18 is adhesively secured to the wall section 17 to provide a substantially flat double walled end supporting ledge 21.

The top end member 12 preferably is formed from a one-piece fibrous blank 22 of sufficient dimension to provide when folded the end member 12 at one end of the blank and an overcap 23 at the other (Fig. 3). The top end member 12 is flat and unindented, is rectangular in configuration and is substantially of the same size as the area defined by the outer peripheral edge of the supporting ledge 21 to which it is to be secured. The top end member 12, adjacent one corner of its free end, as best shown in Fig. 3, is formed with a circular filling and dispensing opening 24.

The overcap 23 is integrally connected with the top end member 12 as an extension thereof, along a line of fold 25 which defines a side edge common to the top end member and to the overcap (Figs. 1, 2 and 3). The overcap 23 is adapted to cover and to protect the top end member and to keep it clean and sanitary. Hence for this purpose the overcap 23 also is rectangular in shape and slightly larger than the top end member 12 so that it may be folded down in overlapping relation upon the top surface of the top end member and over certain of the surrounding peripheral edges of the container.

Adjacent the line of fold 25 a portion of the overcap 23 is additionally secured to the top end member 12 by a narrow strip of adhesive 26 (Figs. 2 and 3). The overcap 23 is adapted to be lifted or swung back from its overlapped position on the top end member to expose this member and the filling and dispensing opening 24 for the purpose of filling products into a container to which such an end is secured and for the dispensing of the products therefrom. Hence, the overcap is formed with a crease line 27 disposed adjacent the adhesively secured portion thereof and along which the overcap 23 is hingeable as best illustrated in Fig. 1.

The filling and dispensing opening 24 in the top end member is closed by a hingeable closure plug or reclosure element 28 which is formed with a countersunk friction plug 31 which fits snugly in and closes and seals the dispensing opening 24. This element is formed with an opening tab 32 and an oppositely disposed tail or hinge lug 33. The hinged closure element 28 is secured to the top end member 12 by a wire staple 34 which extends from the hinge lug 33 down through the top end member and is bent back against the lower surface thereof, permitting the closure element 28 to be swung up and back to facilitate both operations of filling and dispensing of the container contents.

The hinged closure element 28 is assembled to the top end member to provide a unitary or composite closure prior to assembly with the container body 11. When such a unitary closure is applied to the container body 11, the top end member 12 covers and seals the entire mouth of the container as best illustrated in Figs. 1 and 2. When assembled to the container this unitary closure is permanently secured to the flat double walled end supporting ledge 21 by a liquid proof adhesive 35 forming an overlapped double joint

or end seam 36. The outer periphery of this seam preferably is in vertical alignment with the outer surface of the side walls 13 of the container body.

Figure 1 of the drawings illustrates the unitary closure structure after its assembly onto the container body and discloses the flat top, free of indentations or recesses and providing a substantially sterile area over which the container contents may be poured without contamination during a dispensing operation.

Following the assembly of container parts as hereinabove described and while the container is still in the container manufacturer's plant, the entire container and composite end closure preferably is coated inside and outside with paraffin wax or other suitable sterile coating material for rendering them liquid and moisture proof. The friction plug 31 is then inserted into the opening 24 and the overcap 23 is folded down over the top of the container. The completed containers thus temporarily closed and sealed are shipped to dairies for filling.

At the dairy, the hingeable overcap 23 and the closure element 31 are swung back exposing the opening 24 and the container is filled. While the container is open during the filling operation or during dispensing when the container is tilted into the usual pouring position, the hingeable overcap serves as a shield for preventing any matter on the top surface of the overcap from entering the container or from falling onto the clean and sanitary surfaces thereunder. After filling, the container is reclosed by replacement of the friction plug 31 into the opening 24. The friction plug 31 then is expanded to form a holding bead 37 (Fig. 2) which secures the plug in place.

Following the sealing of the friction plug, the overcap 23 is folded down on the top end member 12, over the top of the friction plug 31 and is secured in place by curling or crimping over and under the end seam 36 (Fig. 2), marginal edge portions or flanges 38 which extend laterally from the overcap along the three free edges thereof. These crimped over flanges retain the overcap in place during handling of the container while in shipment and storage and until opened by the consumer.

As an alternative or modified form of the invention Figs. 4 and 5 of the drawings disclose a hingeable overcap 41 which is similar in many respects to the overcap 23 hereinbefore described. The overcap 41 is arranged to cover and protect the top end member to maintain it clean and sanitary and to provide a friction plug closure 42 integral therewith, which plug registers with the filling and dispensing opening in the top end member for closing and sealing it.

The friction plug 42 of such a container is lifted from the filling and dispensing opening in the top end member when the overcap 41 is swung up and back upon arrival at a dairy for filling purposes. The closing operation of the filled container includes the overlapping of the overcap 41 and its engagement over the entire top surface of the top end member.

The expanding of the reclosed friction plug 42 is carried on in substantially the same manner to that already described for the preferred embodiment of the invention and thus forms a holding bead 43 (Fig. 5). This holding bead cooperates with a crimped over section 44 around the end seam in maintaining the hingeable overcap in protective position on the sealed container.

As another alternative or modified form of the invention Figs. 6 and 7 of the drawings disclose an overcap 46 which is similar in some respects to the overcaps 23, 41 hereinbefore described in that it is formed as an integral extension of the top end member. The overcap 46 includes a triangular portion 47 permanently secured to the top end member and a free triangular portion 48 which is hingeable relative thereto and to the container body for covering and for exposing a part of the top end member surrounding the filling and dispensing opening.

The triangular portion 47 is connected to the top member along a line of fold 51 at one side edge of the container remote from the filling and dispensing opening. This triangular portion is secured to the top end member adjoining the folded side edge 51 and to an adjacent side edge 52 by a narrow strip of adhesive 53 bordering upon the edges 51, 52 between these two layers (Fig. 7).

The free triangular portion 48 is hingeable along a crease line 54 which extends diagonally across the top of the container between its opposite corners. The hingeable portion 48 is formed in a suitable manner to provide a countersunk friction plug 55 integral therewith, which plug registers with the filling and dispensing opening in the top end member for closing and sealing the container.

The friction plug 55 is lifted from the filling and dispensing opening when the triangular hinged portion 48 is swung up and back for exposing the opening for filling purposes. During the closing and sealing operation the triangular hinged portion 48 is overlapped upon the exposed part of the top end member and the friction plug 55 reinserted within the filling and dispensing opening for closing and sealing the container.

The expanding of the reclosed friction plug 55 is carried on in substantially the same manner as in the other embodiments hereinbefore described and thus forms a holding bead 56 (Fig. 7). This holding bead 56 co-operates with a crimped-over flange section 57 along adjacent side edges 58, 59 of the triangular hinged portion 48 for retaining this portion in protective position on the sealed container.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A fibre container for liquids, comprising a tubular body, and a separate substantially flat multi-layer end member permanently secured to an end of said body in a laterally projecting end seam, the inner layer of said end member being substantially co-extensive with and secured to the end of said body and having a filling and dispensing opening therein, a plug closure member hingeably secured to the inner layer of said end member for closing and sealing said opening, the outer layer of said end member constituting an integral hingeable overcap extension of said inner layer reversely folded adjacent the outer edge of said end seam and superposed over the inner layer to protect the latter and said plug closure member from contamination, the free marginal edges of said hingeable overcap being folded over and

5 around said projecting end seam to removably secure the overcap in protective position, rearward hinging movement of said overcap relative to the inner layer of said end member providing access to said plug closure for opening the latter to fill and dispense the container contents through said opening.

2. A fibre container for the packaging and dispensing of liquids, comprising a tubular body of rectangular cross section, and a separate substantially flat rectangular multi-layer end member permanently secured to an end of said body in a laterally projecting end seam, the inner layer of said end member being substantially co-extensive with and adhesively secured to the end of said body at said seam and having a filling and dispensing opening therein, a plug closure member hingeably secured to the inner layer of said end member for closing and sealing said opening, the outer layer of said end member constituting an integral hingeable overcap extension of said inner layer reversely folded adjacent the outer edge of said end seam and superposed over the inner layer to protect the latter and said opening from contamination, the free marginal edges of said hingeable overcap extending from opposite ends of said line of fold on adjacent sides of the container being crimped over and around said projecting end seam to removably secure the overcap in protective position, rearward hinging movement of said overcap on said line of fold providing access to said plug closure for opening the latter to fill and dispense the container contents through said opening.

3. A fibre container for liquids, comprising a tubular body terminating at its upper open end in an outwardly projecting coplanar peripheral ledge, and a separate substantially flat end member of integral inner and outer layers secured to said open body end, the inner layer of said separate end member being substantially co-extensive with and permanently adhesively secured at its marginal portions to the outer surface of said body ledge to constitute therewith an outwardly projecting end seam, said inner layer having a filling and dispensing opening therein, and a plug closure for said opening supported by one of said layers, the outer layer of said separate end member constituting an integral overcap extension of said inner layer reversely folded and superposed over the inner layer to entirely cover and protect the latter and said opening from contamination, the free marginal edges of said overcap being folded over and around a portion of said projecting end seam to removably secure the overcap in protective position, a portion of said overcap extension being hingeable outwardly relative to said inner layer to provide access to said opening for filling and dispensing the container contents.

4. A fibre liquid container as defined in claim 3, wherein said tubular container body is of rectangular cross-section.

5. A fibre liquid container as defined in claim 4, 65 wherein said plug closure for the filling and dispensing opening constitutes an integral depending portion of said overcap extension, and the free marginal edges of said overcap on three adjacent sides thereof being folded over and around the three subjacent edges of said end seam for the purpose described.

6. A fibre liquid container as defined in claim 4, wherein said overcap extension includes a fixed triangular portion permanently adhesively secured to the inner end member layer along two

adjacent side edges remote from the container opening and a movable triangular portion integral with and hingeable on said fixed triangular portion to overlie said opening, adjacent side edges of said movable triangular portion being folded over and around the subjacent side edges of said end seam, said plug closure being formed as an integral depending part of said movable triangular overcap portion.

RUSSELL C. TAYLOR.
